UNITED STATES PATENT OFFICE.

CHARLES W. LEWIS, OF NASHVILLE, TENNESSEE.

RADIATOR COVER.

Application filed January 6, 1923. Serial No. 611,149.

To all whom it may concern:

Be it known that I, CHARLES W. LEWIS, a citizen of the United States of America, residing at Nashville, in the county of Davidson and State of Tennessee, have invented certain new and useful Improvements in Radiator Covers; and I do hereby declare that the following is a full, clear, concise, and exact description of the invention, such as will enable others skilled in the art to which it appertains to make and use the same.

This invention relates to improvements in household furnishings, having for an object to provide a novel and decorative article of furniture particularly advantageous and desirable for covering and concealing radiators in homes and like dwellings, thereby lending to the artistic appearance of a room and its decorations.

It is also an object of the invention to provide a radiator cover of the character mentioned so constructed as to permit of an ample supply of cold air to the radiator for radiation and likewise, to allow the heated air to be freely radiated from the same, hence ensuring proper functioning of the radiator as well as the heating of the room to that temperature desired.

Other objects will be in part obvious and in part pointed out hereinafter.

In order that the invention and its mode of operation may be readily understood by persons skilled in the art, I have in the accompanying illustrative drawings and in the detailed following description based thereon, set out one possible embodiment of the same.

In these drawings:

Figure 1 is a front elevation of the improved radiator cover;

Figure 2 is an end elevation thereof;

Figure 3 is an enlarged fragmental detail in section showing the construction of one of the end walls of the cover;

Figure 4 is a vertical transverse section through the device;

Figure 5 is a vertical longitudinal section therethrough;

Figure 6 is a fragmentary detail in elevation showing the nature of the material employed in constructing the device; and,

Figure 7 is an enlarged fragmentary detail in perspective showing the formation of the upper ends, of one of the side and of one of the end walls of the device.

Having more particular reference to the drawings, in connection with which like characters of reference will designate corresponding parts throughout, the improved radiator cover may be stated to comprise a shell-like body indicated in its entirety by the numeral 1, including side and end pieces 2 and 3 respectively and a top covering 4; the lower portion or bottom of the shell-like body being open as shown in the Figure 4, whereby the same may be readily placed over a radiator to be shielded therein.

In constructing the improved radiator cover, I preferably employ a sheet metal having a covering of baked porcelain finished or colored as may be desired in the decorating of a room. In this connection, it will be appreciated that the surfacing coating of baked porcelain will render the radiator cover impervious to the detrimental action of such heated air as may be radiated thereon, since, it has been found that the surfacing coating of baked porcelain requires approximately twenty-five hundred degrees Fahrenheit to melt the same.

The end pieces 3 of the radiator cover are adapted to be slipped over the opposite end portions of the sides 2 and as shown, certain of the marginal portions of said end pieces 3 are provided with right angularly bent portions 5 adapted to overlap the adjacent portions of the side wall 2, while other portions of said end pieces are formed with substantially right angularly shaped elbows or lips 6 adapted to abut against inwardly disposed or right angularly arranged lips 7 formed upon the adjacent portions of the front side wall 2 of the device. Any suitable form of fastening means may be employed for connecting the end pieces 3 to those portions of the side pieces or walls engaged thereby, such as conditions or preference may dictate.

Furthermore, the front side piece or wall 1 and the several end pieces or walls 3 are provided with openings or cut away portions 8 adjacent their upper ends whereby to provide ways which will permit of the egress or radiation of heated air given off by a radiator housed or concealed within the radiator cover. Also, the front side piece or wall 2 of the device is provided with a plurality of ornamental devices 9, herein shown as resembling the handles of sliding drawers and beneath or directly rearwardly of these devices 9 openings 10 are formed

to permit of further ways for the egress or radiation of heated air from the radiator cover. In this way, it will be understood that with the arrangement of the improved 5 radiator cover over a radiator, proper functioning of the latter will be permitted at all times and hence, the heating of a room receiving the same to the temperature desired will be ensured.

10 With a view towards providing means for facilitating the adjustment or control of the usual hand operated valve of a radiator, an opening is preferably formed in one of the end pieces 3 of the device and if desired, 15 may be covered by an ornamental swinging or pivoted cover plate 11. The size of this opening is such as will permit the insertion of a person's hand therethrough whereby the radiator valve handle may be grasped 20 and operated as may be desired.

As hereinbefore stated, the device will permit of an ample supply of cold air to the radiator whereby to effect radiation and in order that this supply may be positively 25 effected, I may and preferably do form recesses or ways 12 in the lower portions of the side and end pieces 2 and 3, hence affording unobstructed passage ways for the conduction of cold air within the radiator 30 cover to the radiator concealed therein.

While I have herein described with some degree of particularity, one form of my improved radiator cover comprising a body including end and side walls and having ornamental devices upon one wall thereof resembling sliding drawers, it is to be fully understood that the particular design of the device may be varied, such as conditions or preference may dictate. This will be found 40 to be especially true when the device is desired to be used in the artistic decorating of a room, wherein it will be desired to match the furniture of the room and the radiator cover. Because of this, I find it practical to 45 quite often vary the ornamental design of the radiator cover, as for example to form the same as an article of period furniture or the like at certain times and as various other articles at other times. Likewise, the 50 color of the radiator cover may be made to correspond or blend as may be desired, with the principal furnishings of a room receiving the same. Therefore, it will be under-

stood that the underlying principle or fundamental feature of my improved radiator 55 cover may be stated to reside in the provision of a shell-like body formed of sheet metal provided with a colored baked porcelain surfacing material, the shell-like body being provided with ample means to permit 60 the ingress of cold air for radiation purposes and other ways for the egress of heated air or radiation from the device. Obviously, the particular form or arrangement 65 of ways for permitting the ingress and egress of cold and heated air from the radiator cover may be varied as well as the ornamental design or appearance of the shell-like body.

Manifestly, the construction shown is capable of considerable modification and such modification as is within the scope of my claim, I consider within the spirit of my invention.

I claim:

A radiator cover comprising end and side walls of sheet material, the lower portions of said end and side walls having recesses therein forming ways for ingress of air, the forward side portions of said end walls 80 having lips formed thereon substantially right angular in cross section, the opposite sides and adjacent portions of the forwardly disposed side wall having right angularly disposed lips thereon abutting and flushly 85 engaging portions of said right angularly formed lips on the end walls, the rearward side portions of said end walls having in-turned right angularly disposed portions thereon overlapping the adjacent portions 90 of the opposite ends of the rearwardly disposed side wall, parts of said end and front walls being extended for corresponding distances above their respective upper marginal portions, and a top covering having 95 downwardly disposed flanges formed upon certain of its marginal portions engaged over the upper portions of said end and side walls and resting upon said extensions, the flanges on said top covering being disposed 100 laterally of and overlying the opening formed in said side and end walls between said extensions.

In witness whereof I have hereunto set my hand.

CHARLES W. LEWIS.
